UNITED STATES PATENT OFFICE.

ADELBERT SMITH, OF SEWARD, NEW YORK.

VENDING-MACHINE.

No. 846,356.

Specification of Letters Patent.

Patented March 5, 1907.

Application filed April 26, 1904. Serial No. 205,007.

To all whom it may concern:

Be it known that I, ADELBERT SMITH, a citizen of the United States, residing at Seward, in the county of Schoharie and State of New York, have invented a new and useful Improvement in a Vending-Machine, of which the following is a specification.

This invention relates to that class of coin-controlled apparatus designed and adapted for the sale of cigars, chewing-gum, and similar light articles.

The object of the invention is a device of this character containing but little mechanism, and that of the simplest character, thereby providing a vending-machine which can be built at a small cost and which is not liable to get out of order and which if broken may be easily and cheaply repaired.

The invention also consists in the novel construction and combination of parts hereinafter described, particularly pointed out in the claims, and shown in the accompanying drawings, in which—

Figure 1 is a perspective view of my vending-machine. Fig. 2 is a vertical section through the machine. Fig. 3 is a section on an irregular line taken horizontally through the lower portion of Fig. 2. Fig. 4 is a detail view showing the side guide arranged in the inclined portion of the goods-chute. Fig. 5 is a detail perspective view showing the adjustable guide arranged in the vertical portion of the goods-chute. Fig. 6 is a detail plan view of the bar supporting the guide, parts being broken off and the guide being shown in cross-section. Fig. 7 is a detail perspective view of the lower end of the coin-chute and the tripper-bar pivoted below the chute, the whole being shown removed from the machine.

In the drawings, A represents a casing of any desired size, shape, and material. I have shown such a casing divided by a vertical partition B into two separate vending-machines, cigars being vended from one of the compartments or sides and chewing-gum from the other, and the operating mechanism is practically duplicated on each side of the partition B. The casing A is further subdivided by a vertical partition C, extending from side to side of the machine and at right angles to the partition B. The partition C divides the machines or casing A into front compartments, in which the goods to be vended are contained, and the rear compartments, in which I have shown vertical coin-chutes D,

one on each side of the partition B. The partition B extends vertically from top to bottom of the casing A; but the partition C is arranged vertically in the middle body portion 60 of the casing and is thence angled outwardly or forwardly, as shown at C' in Fig. 2, and at its lower end it is also brought forwardly and downwardly, as shown at C², and at its lower forward end it connects with the curved 65 metal plate C³, which extends to the bottom and front of the machine and forms an upwardly open trough C⁴, into which the goods vended are delivered.

A front E is secured to the casing A in advance of and practically parallel with the various portions C, C', and C² of the partition above described, and portions of this front may be formed of glass panels E', as shown in the drawings. The space inclosed between the front E and the partition-walls C, C', and C² will be termed the "goods-chute."

Referring to details of construction, in the upper forward portion of the casing A an inclined base F is supported above the partition-wall C' and is adapted to support a cigar-box F', cut out in the bottom adjacent one end to aline with the upper end of the goods-chute. To properly guide the cigars down this chute and also to accommodate 85 the chute to cigars of various lengths, I provide transverse metal bars G, extending crosswise of the chute and slotted, as shown at G', a slot being formed adjacent each end of the bar, and I provide guide-bars H, adapt- 90 ed to rest vertically in the sides of the goods-chute and having inwardly-projecting arms H', connected rigidly to the guide-bars H and adapted to slide on the bars G, to which they are connected by screws, the shanks of 95 which work in the slots G', allowing a limited movement of the guide-bars H and arms H'.

The uppermost arm H' has a wire J connected thereto, a wire and arm being arranged on each side of the goods-chute, and the wire J 100 passes downward in advance of the partition-wall C, and under the lower arm H', above the wall C², and in advance of the arm H', last mentioned, the wire is bent back upon itself and curved upwardly and forwardly, as 105 shown at J'.

To the upper ends of the vertical guide-bars H are hinged the guide-arms H², which project into that portion of the goods-chute formed by the wall C' and the front of the 110 casing parallel to said wall, and it is understood that the guides H and arms H² lie ad-

adjacent the sides of the casing A and are movable toward each other. It is evident, therefore, that by adjusting the guide-bars H toward or away from each other the width of 5 the goods-chute is decreased or increased, and goods, such as cigars, of various lengths are accommodated with a passage-way of the proper width. The cigars or other articles fill the goods-chute, being arranged in vertical alinement between the walls C' and the front E, and after passing into the portion of the chute between the glass panel E' and the wall C they travel between the said wall and the wires J, the latter pressing sufficiently 10 upon the goods to prevent their displacement. The delivery mechanism is as follows: A shaft K is arranged in the casing A parallel to the rear wall of the casing and slightly in advance of the coin-chute D. A 15 lever L is pivoted intermediate its ends on the shaft K, the lever being duplicated for each coin-chute, and the rear end of the lever lies immediately below and in alinement with the lower end of the coin-chute. The forward end of the lever supports a wire frame M, originally rectangular in shape and having one-half of the frame bent longitudinally 20 at right angles to the other half. The free ends of the wire forming the frame are twisted 25 to form a supporting-leg M', which leg is pivoted to the front end of the lever L, and the frame M tends by gravity to tilt forwardly. This frame is projected upwardly through a slot N, formed in the wall C², the 30 upper bent portion lying normally flush with the upper surface of the wall C². A fender O is arranged on the wall C² immediately in advance of the slot N. The upper portion of the chute D is curved, and when the chute is 35 designed for the reception of five-cent pieces I form a slot D' in the curved portion of the chute, through which coins of the denomination of one cent will fall, while those of the size of a five-cent piece will travel downwardly through the chute and fall upon the 40 45

lever L, throwing the lower end of the same downward and the forward end upward. The lowermost of the articles to be vended by the machine will rest upon the upper bent portion of the frame M, and the upward movement of the lever L will lift the frame and article above the upper edge of the fender O, and the article will roll into the trough C', from which it is removed by the purchaser. The coin will fall from the end of the lever L 50 into a coin-box P, and the parts will assume their original position by action of gravity. No springs, gears, pawls, or ratchets are employed, and there is but little mechanism to get out of order, and the arrangement of the 55 parts are so simple that they can be easily repaired or replaced. It will be obvious that as many goods-chutes may be arranged in a casing as may be desired.

Having thus fully described my invention, 60 what I desire to secure by Letters Patent is—

1. A vending-machine comprising a goods-chute, inwardly-movable guide-bars arranged within the chute, inwardly-extending arms carried by the guide-bars, guide-rods carried 70 by the arms and parallel to the front of the chute, and means for delivering goods from the said chute.

2. A vending-machine comprising a goods-chute angled at its lower end, a trough upwardly open in advance of the lower end of the chute, the rear wall of the chute being slotted in the angled portion, adjustable guide-bars arranged in the chute and adapted to vary the width of same, wires carried by 80 the said bars and running lengthwise of the chute, a fender arranged in the chute in advance of the slot, and means working through the slot adapted to lift articles to be vended to a plane above the upper edge of 85 the fender, as and for the purpose set forth.

ADELBERT SMITH.
